STORAGE RACK FOR ROLL GOODS OR CARTONS, OR THE LIKE

Kenneth William Baxter, Burbank, Calif.
(1209 Air Way, Glendale, Calif. 91201)

Filed June 20, 1969, Ser. No. 17,786

Term of patent 14 years

Int. Cl. D6—99

U.S. Cl. D33—3

FIG. 1FIG. 2FIG. 3

FIG. 1 is a front perspective view of a storage rack for roll goods or cartons, or the like embodying my new design;

FIG. 2 is a front perspective view of a modified form of the storage rack for roll goods or cartons, or the like shown in FIG. 1;

FIG. 3 is a front elevational view of the rack shown in FIG. 1;

FIG. 4 is a side elevational view of the rack shown in FIG. 1; and

FIG. 5 is a top plan view of the rack shown in FIG. 1.

I claim:

The ornamental design for storage rack for roll goods or cartons, or the like, as shown.
